UNITED STATES PATENT OFFICE

2,579,605

BUILDING OF NONPERMANENT BRIDGES
CHIEFLY FOR MILITARY PURPOSES BY
MEANS OF AMPHIBIAN SEAPLANESCharles Alexis Marie Eugène Odot,
Hussein-Dey, AlgeriaApplication June 27, 1946, Serial No. 679,654
In France December 20, 1944Section 1, Public Law 690, August 8, 1946
Patent expires December 20, 1964

10 Claims. (Cl. 244—1)

1 My invention has for its chief object the arrangement of airplanes, seaplanes, gliders and the like with a view to their use in the building of non-permanent bridges for the crossing of rivers, streams and the like stretches of waters by convoys.

Although chiefly intended for wartime requirements, my invention may be used in peace time for restoring interrupted communications from one side of a river to the other.

Said invention has for its object the hastening of the positioning of the crossing means, with the removal of the necessity of road transportation which is always long, costly and dangerous while obtaining the surprise effect necessary for all war operations.

It will considerably increase the speed of modern ironclad divisions and substantially improve their radius of operation.

The principal advantageous features of the arrangements provided for the airplanes, seaplanes or gliders are as follows:

(a) They are amphibian.

(b) They permit without any additional reinforcing of the floating capacity, the passage of light convoys.

(c) Their floating capacity may be increased, through the incorporation of both light and powerful carriers such as pneumatic boats, for allowing the passage of heavy convoys.

(d) Connecting means at the ends of the wings allow their interconnection for forming a continuous rolling way or track over a plurality of seaplanes secured together endwise and connected to the banks by means of stationary or semi-movable trusses, thus forming the bridge considered as a whole.

(e) The wings of the aircrafts are specially designed so that they may resist the aerodynamic stresses during flight and also the stresses due to rolling loads when the aircrafts are used in the constitution of a bridge. The passage of the convoys is permitted lengthwise over such wings which form a part of the usual trusses of a bridge.

(f) A horizontal rolling surface and a sufficient breadth of way are obtained through special means such as an opening pneumatic wing the tail end of which may be inflated to a variable extent or tubes receding in flight and adapted to carry a flooring.

I have shown by way of example in accompanying drawings a form of execution of my invention allowing its characteristics features to appear clearly without it being necessary to enter

2 with further detail into the manner of using same. In said drawings:

5 Fig. 1 is a general elevational view of a bridge constituted by two seaplanes and including various types of seaplanes.

10 Fig. 2 is a plan view corresponding to Fig. 1 wherein one part of the seaplane is shown as ready for flight and another with its wing open and the flooring removed, a third part being shown with the flooring in place.

Fig. 3 is a view of the seaplane on a supporting member in vertical cross-sectional through line III—III of Fig. 1.

15 Fig. 4 is a sideview of the aircraft ready to fly.

Fig. 5 is a cross section through line V—V of Fig. 1 of one of the seaplanes.

20 Fig. 6 is an elevational frontview of the connecting means between a seaplane and a movable bridge truss.

Fig. 7 is a vertical cross-section through the broken line VII—VII of Fig. 8, showing the two cockpits of a seaplane and one half of the roller bridge carried thereby.

25 Fig. 8 is a plan view of these cockpits together with one half of a supporting craft and one half of the operative platform.

Fig. 9 is an elevational view of a girder connecting a seaplane to moorings located on a high bank.

30 Fig. 10 shows two girders carried by a frame and connecting the seaplane with moorings located on a bank of average height.

Fig. 11 is a vertical cross-section of a wing supported by a pneumatic boat.

35 Fig. 12 is a corresponding plan view showing only one half of the boat.

Fig. 13 shows the connection between a girder and the end of a wing which latter is seen in vertical cross-section.

40 Fig. 14 is a half elevational, half cross-sectional view of the connection between two wing ends in alignment with predetermined girders.

Fig. 15 is a vertical cross-section of the two cooperating ends of adjacent wings in vertical alignment with another girder.

45 Fig. 16 is an end view partially cross-sectional corresponding to Fig. 15.

Figs. 17 and 18 are similar to the preceding figures, and correspond to a further girder.

Fig. 19 is a vertical cross-section executed through the axis of one of the girders and shows the pivoting means between an abutment wing of a seaplane and its hydraulic raising means.

Fig. 20 is a side view of a glider forming part of a bridge.

Fig. 21 is a half plan view of an aircraft ready for flight.

Fig. 22 is a half plan view of the same aircraft forming part of a bridge.

Fig. 23 is a half elevational view of a further flying machine.

Fig. 24 is a half longitudinal elevational view of the same flying machine forming part of the bridge.

Fig. 25 is a side view of a machine ready to take off.

Fig. 26 is a half sectional view of a recess body forming a pneumatic raft.

Fig. 27 is a half view through the front of the same recess body.

Fig. 28 is a transverse elevation of the end portion of a recess body.

Figs. 29 and 30 are cross-sections of the wings showing diagrammatically different arrangements of the cross beams and roller ways.

Fig. 31 is an elevational view of a securing hook.

Fig. 32 is a cross section of the hinge of the opening wing on the side corresponding to its trailing edge.

My invention allows providing for the passage of loads up to 50 tons and it is even probable that this estimation may be widely increased in further developments. The size of the apparatus will depend upon the type of convoys which are to cross over the projected bridge.

The seaplanes or gliders used may be provided with one or more cockpits. Recesses are provided for retractable landing wheels 1 (Fig. 4). The landing gear may also be cast off. Sea-faring propellers are also provided. In addition to the cockpits, pneumatic crafts 2 (Figs. 1, 3, 11 and 14) ensure the floating capacity of the system. Each craft carries a weight distributing flooring including boards 3 (Figs. 11, 12 and 14), joined together and covered with sheet metal at 4. Two I beams 5 (Figs. 11 and 12) or trellis girders of lesser weight serve for the distribution of the stresses over said flooring. When gliders are used, pneumatic floats 11 (Figs. 22 and 24) are folded inside the recesses or chambers 12 (Fig. 23) arranged underneath the wings. Their inflating valves are connected to a pipe feeding compressed air thereto. As soon as the pressure is sufficient, the casings forming the recesses open automatically and the floats find their proper place underneath the wings as shown in Figs. 22 and 24.

The body of each of these recess-forming casings 13 (Fig. 28) may be made of wood or metal blades and once open said recess casing bears against the lower surface of the wing along a plane. The two streamlined ends should be executed so as to hold the recess-forming body described hereinabove closed during flight.

The sending of compressed air into the feed pipe causes the ends of the recess bodies to slide over the slideways 14 (Figs. 26, 27 and 28) prepared to this end and as the blades are released through their ends the recess will then be open. A return spring (Fig. 28) returns each end into its original position as soon as the pressure is removed.

The wings of the seaplanes bear on the boats through the agency of supports constituted by small posts 6 (Figs. 1, 10, 11, 14, 17 and 19) made of sheet iron; the upper end of each of these posts may be connected through a pin 7 (Figs. 11, 14 and 15) to the girder system inside the wing so as to allow the small post to recede during flight inside a recess on the underside of the wing. The height of these small posts or bearing members is variable. Their hemispherical lower ends rest inside

the recesses formed in a support 8 secured to the flooring of the corresponding boat (Fig. 11). The small terminal posts at the ends of the wing may be coupled with those of the adjacent machine so as to rest together on a single boat as shown in Fig. 14. An oval opening allows securing thereto through the agency of the pin 10 the girder forming part of the connecting means to be described hereinafter.

The system of floating trusses is constituted as shown in Figs. 2 and 11 by four girders 25, 26, 27, 28, arranged inside the wing of each sea-plane in the longitudinal direction thereof, said girders serving also as spars for the central compartment.

These beams are interconnected through stays 29 carrying the flooring 30 made of striated sheet metal. The height of each girder is defined through its location in the transversal outline of the wing. The upper limb of each girder matches the shape of this outline while the lower limbs include recesses inside which the supports or posts 6 are retracted during flight as shown in Figs. 14 to 18.

In order to allow the passage of rolling loads over the flooring 30, the wing opens through its upper part as shown in Figs. 2, 3 and 11. The hinge 31 connected with the edge of the girder 27 is designed in a manner such that it does not project above the flooring 30 (Fig. 32).

When the wing is hinged open as shown in dotted lines in Fig. 32, the pivoting plate 30a is folded towards the trailing edge and rests on studs 32 distributed in the same manner as the stays 29.

The hinge 33 of the pivoting plate 30b adapted to be folded towards the leading edge shows no particular feature of interest.

During flight, the wing is closed; a felt 34 (Fig. 32) is placed over the flooring before it is closed 40 so as to form an elastic cushion which reduces the vibrations of the pivoting plates.

Bolts are adapted to secure rigidly the edges of said pivoting plates to the girder 26. A plate 35 of light sheet metal covers the projecting part of the hinge 31 in order to direct the streamlets of air above said projecting part.

The use of so-called shell wings may also be contemplated.

The number of compartments to be executed 50 will depend on the nature of the convoys which are to pass over the bridge.

For the constitution of stationary trusses, the male ends of the bank girders enter the recesses 40 at the ends of the wings and bear against the supporting trunnions 41 (Fig. 13). In the case of stationary trusses a male end will be associated with a female end for each supporting shoe.

The floating trusses form generally the major part of the bridge; the inclines leading to the bridge are generally constituted by stationary trusses. Semimovable trusses connect the floating trusses with the stationary trusses (Fig. 10) or with the moorings (Fig. 9).

The bearing arrangement at the junction of two 65 wings is illustrated in Fig. 14 and includes a stationary girder 42 connected with the small posts 6 at the end of the cooperating wings through the pins 10; the latter passing through the oval openings in the posts are given the play necessary 70 which allows the wings to assume a slight slope with reference to one another while remaining in contact or at a distance corresponding to a small play between them; this girder 42 is connected through the rods 43 to a pivoted girder 75 44 held spaced with reference to the former girder

by a spring 45 surrounding the rods 43 which latter may slide inside a recess 46 inside the pivoted beam 44. Two other springs 47 are arranged round the rods 48 which limit their expansion; said springs may be removed in order to allow the introduction and positioning of the terminal posts 6 of the wings and said springs are reinserted as soon as said operation is at an end. Studs and securing screws 49 hold them fast.

Between the two cockpits of each seaplane (Figs. 7 and 8) is provided a platform allowing the assembly and the inflation in an easy manner of the pneumatic boats before they are launched. Said platform is constituted by a flooring 50 of light sheet iron which may be removed so as to allow the taking off of the aircraft and by I beams 51 connecting the two cockpits and holding them at the desired spacing. A controlling motor-driven launch may be secured rigidly to said cross-beams and be carried off by the seaplane; it is used for anchoring and positioning the pneumatic boats in the building of the bridge.

In the case where seaplanes are used with a treble cockpit, it is possible to provide two platforms so as to make operation easier.

Two systems of rails 53 and 54 arranged in parallelism between the cockpits allow the use of two roller bridges 55, 56 carrying winches and adapted to make the launching of the pneumatic boats and of the launch easier.

The opening and the closing of the opening parts of the wing may be executed by means of mechanically driven winches arranged inside the wings. The pivoting plates may be subdivided longitudinally into as many panels as may be necessary for making their operation easier.

A loading mast of light trellis work 60 (Fig. 6) may also be arranged on the top of the wing so as to supplement the winches if required.

Fig. 31 illustrates the hooks 57 connected through a left and right handed screw 58 which allows moving them near one another after they have engaged the trunnions 59 located at the ends of adjacent wings so as to adjust the distance between the latter (Fig. 14).

For adjusting the slope of a movable wing (Fig. 19), it is possible to use a hydraulic press 61 or a screw winch connected through a rigid rod 63 to a pivot 64 secured to the underside of the girder 25.

Without widening the scope of the invention, it is possible to make use of bi-plane seaplanes capable of carrying heavy loads and of landing at a slow speed or alighting on restricted stretches of water. In this case, it is possible to include the limbs of a trellised glider in each plane of the seaplane, and to design the bracing so as to cause the uprights and diagonal members of said girder to form part of the bracing.

The use of gliders (Fig. 20 and following figures) reduces the cost price, the dead weight and the resistance to the impact of wind, which are detrimental for a correct anchoring. Said gliders may take off from a normal aviation landing ground through the agency of a set of wheels 37 (Fig. 25) which may be retracted or cast off; they may alight through the agency of their cockpit, watertight wings and float system 38 (Figs. 20, 21, 22 and 23) of a special design and also land on flat unprepared ground through the agency of shoes 64a—64b (Figs. 20 and 25).

Each glider is provided with a removable tail 65 (Figs. 20, 21, 22 and 25) adapted to be easily

6
dismantled and set aside as soon as it is laid over water.

Part 66 of the body or cockpit is also designed so as to allow its easy removal whereby the passage required for the rolling load is set free. It will be noted that the upper part of the body of the glider projects above its wings, and that its removable section 66 (Fig. 25) is disposed above the flooring or track area (see Fig. 20).

10 The wings may be separated from the cockpit in order to make the folding of the bridge and the transportation on road easier after the constitutive elements have been used whereby it is possible to bring same to the nearest aerodrome where the aircraft may be erected again in view of a further operation.

15 The wings and the cockpit are watertight and may be subdivided by partitions into independent compartments. They may be submerged. A type of wing merely canvassed which is extremely light may also be contemplated. The wings are provided at their lower surface with a series of floats 38 (Figs. 20, 21, 22 and 23) designed so as to allow the aircraft to float with its wings above water when it is not overloaded. They also include under their lower surfaces recesses 12 with pneumatic floats (Fig. 23).

20 Other pneumatic floats 67 of suitable shape (Figs. 20, 29 and 30) may be inserted at the rear of the wing for increasing the floating capacity, and the stability of the system. They are merely slid underneath the armatures 68 (Figs. 20, 21, 25, 29 and 30) made of metallic tubes and adapted to be permanently secured over the wing or else lying against same during flight. The floats are then inflated and held in place through mere friction.

25 For the passage of the rolling load it is possible to use the opening wing shown in Fig. 22 which provides easily a perfect platform with a track up to 3.60 meters wide, while the part remaining closed is made fluidtight.

30 It is also possible to resort to a system of rolling tracks 70a, 70b, (Fig. 29) made of corrugated sheet metal resting partly on the upper part of the wing and partly on a system of small posts or metallic tubes 69 transmitting these stresses to the girders 71 at the rear of the wing. The rolling tracks 70a, 70b, may be carried along with the glider and positioned at the moment at which the latter is to be used for the construction of a bridge. This system which should be stronger than an opening wing may allow eventually a reduction in the width of the wing.

35 Fig. 30 illustrates the cross-section of a wing adapted to be used alone. It contains a bay adapted to resist the stresses arising from the rolling loads and those arising in flight. It may be rendered fluidtight and its floating capacity will allow it to carry, in addition to its own weight, an overload which is proportional to its volume; it may also be laid on the pneumatic boats of treadway bridges for use as a rolling track. Its lower part which is flat through construction serves as a flooring; the wing should thus be turned upside down before use. It may form the dismountable wing of a glider or the second plane of a biplane aircraft or seaplane, adapted to fly normally as a monoplane. It may thus be brought by air to the point of building of the bridge. Propellers may be used for moving it over water.

40 What I claim as my invention and desire to secure by Letters Patent is:

45 1. A method for building a dismountable trans-

portable bridge across a stretch of water consisting in causing flying machines with floats to alight on said stretch of water, assembling them in side by side relationship with one another and with elements laid on the banks on the stretch of water and arranging the upper surface of the flying machine as vehicle tracks.

2. A method for building a dismountable transportable bridge across a stretch of water consisting in causing flying machines with floats to alight on said stretch of water, assembling endwise the ends of the wings of said machines, connecting the outer ends of the outermost machines thus assembled to bridge elements laid on the banks of the water stretch, providing pneumatic floats underneath the wings for carrying same and laying a vehicle track on the upward surfaces of the wings.

3. In a flying machine adapted to be used as a pontoon in the execution of a dismountable transportable bridge, the combination of a flooring extending above the wings throughout the length thereof and flaps hingedly secured to the front and rear edges of the wings and adapted to be folded above same during flight and to be unfolded to form the sides of a track for vehicles.

4. An airplane intended to be employed as a pontoon in the building of a collapsible and transportable bridge across a watercourse for the passage of rolling loads, the airplane comprising opposed and oppositely projecting wings, a track at the exterior of the wings and extending longitudinally thereof from the outer end of one wing to the outer end of the other wing, the track being so constructed and arranged as to permit the passage of a rolling load along it above the wings, when the airplane is placed on the water with other planes for making a bridge, and a girder system fixed longitudinally to the interior of the wings and so constructed and arranged that it will not only sustain the aerodynamic stresses in the airplane in flight but will also sustain the weight of the rolling loads passing over the track when the airplane forms a part of a bridge.

5. An airplane intended to be employed as a pontoon in the building of a collapsible and transportable bridge across a watercourse for the passage of rolling loads, the airplane comprising opposed and oppositely projecting wings, a track at the top of the wings and extending longitudinally thereof from the outer end of one wing to the outer end of the other wing, the track having a substantially flat and rigid floor surface over which a rolling load may pass above the wings when the airplane is placed on the water with other planes for making a bridge, and a girder system fixed longitudinally to the interior of the wings and so constructed and arranged that it will not only sustain the aerodynamic stresses in the plane in flight but will also sustain the weight of the rolling loads passing over the track when the airplane forms a part of a bridge.

6. A glider intended to be employed as a pontoon in the building of a collapsible and transportable bridge across a water-course for the passage of rolling loads, the glider comprising opposed and oppositely projecting wings which are hollow and have water tight coverings to render the glider buoyant, said wings having flat and coplanar bottom surfaces, a track flooring extending longitudinally along the wings on the exterior of said flat bottom surfaces from the end of one wing to the end of the opposite wing, the track flooring being so constructed and

arranged as to permit the passage of a rolling load along it when the glider is placed on the water in an inverted position and assembled with other gliders for making a bridge, and a girder system fixed longitudinally to the interior of the wings, the girder system being so constructed and arranged that it will not only sustain the aerodynamic stresses in the glider in flight but will also sustain the weight of the rolling loads passing over the track flooring when the glider forms a part of a bridge, the floating capacity of the glider being sufficient to sustain both its weight and that of the rolling loads passing over the track flooring.

15 7. In a collapsible and transportable bridge for crossing a watercourse, the bridge including airplanes arranged on the water with their opposed and oppositely projecting wings in tip-toe relation, the wings having longitudinally extending tracks for the passage of rolling loads over the tops of the wings, the combination of adjacent wings of two adjacent airplanes arranged with the wing ends in opposed relation, a spur fixed adjacent the end of each of said wings, a double-hook connector fitted on the two spurs, a wing-sustaining float beneath the adjacent ends of said wings, two posts having their upper ends jointed near the respective ends of the two wings, said posts being disposed in downwardly converging relation and having their lower ends jointed to each other and supported by said float, and a shock-absorber device carried by the upper portions of the two posts and including spring-actuated, pivotally-connected members which respectively engage the undersides of the end portions of the two wings.

8. A glider intended to be employed as a pontoon bridge in building a collapsible and transportable bridge across a watercourse for the passage of loads on wheels, the glider comprising a body with opposed wings projecting from its opposite sides, the body having its upper portion projecting above the tops of the wings, said wings being hollow and provided with watertight coverings to render the glider buoyant, a girder system fixed longitudinally inside of the wings and extending through the body, two flat floorings spaced for engagement by the wheels of a road vehicle and supported by said girder system, said floorings extending across said body and longitudinally along the upper surface of said wings from the outer end of one wing to the outer end of the opposite wing, the part of the upwardly projecting portion of said body above said floorings being removably mounted, said girder system being so constructed and arranged as to sustain the aerodynamic stresses of the glider in flight and to sustain the weight of the loads on wheels passing over said floorings when the glider rests on water and is assembled with other gliders for constructing a bridge.

9. The structure of claim 5 in which the wings project in opposite directions from a body and the latter contains part of said girder system, means pivotally connecting the girder system portion in at least one of said wings with the girder system portion in said body to permit the outer end of said one wing to be swung vertically, and operating means to adjust the angle of said one wing in relation to the body and the other wing so as to connect the said flooring to watercourse banks at different heights above the water level.

70 10. In a flying machine adapted to be used as

a pontoon in the execution of a dismountable bridge, the combination of an aircraft having a body with oppositely projecting wings having curved air-flow upper surfaces, a girder system within the wings and extending longitudinally thereof, road-vehicle track flooring within the wings and supported by said girder system, said flooring being flat and extending throughout the length of the wings, oppositely folding flaps disposed above said flooring during flight and forming a part of the top surfaces of the wings, and hinged means connecting said flaps to the wings along the outer edges of the flooring to permit said flaps to be swung upwardly to expose said flooring.
